Primary Examiner — Karen S Acker*Assistant Examiner* — Wendy Arminio(74) *Attorney, Agent, or Firm* — Thompson Coburn LLP(57) **CLAIM**

The ornamental design for a hinged bottle closure, as shown and described.

DESCRIPTION

FIG. 1 is a front perspective view of a hinged bottle closure showing our new design;

FIG. 2 is a rear perspective view thereof;

FIG. 3 is a right side elevational view thereof;

FIG. 4 is a left side elevational view thereof;

FIG. 5 is a rear elevational view thereof;

FIG. 6 is a front elevational view thereof; and,

FIG. 7 is a top plan view thereof.

The broken lines immediately adjacent to the shaded areas depict the bounds of the claim and form no part thereof. All other broken lines are environment and form no part of the claimed design.

1 Claim, 7 Drawing Sheets(56)
